UNITED STATES PATENT OFFICE.

JOHN KREHBIEL, OF DETROIT, MICHIGAN, ASSIGNOR TO THE GLOBE CAPSULE COMPANY, OF SAME PLACE.

CAPSULE-CUTTER.

SPECIFICATION forming part of Letters Patent No. 312,361, dated February 17, 1885.

Application filed October 16, 1883. (No model.)

To all whom it may concern:

Be it known that I, JOHN KREHBIEL, of Detroit, in the county of Wayne and State of Michigan, have invented new and useful 5 Improvements in Capsule-Cutters; and I do hereby declare that the following is a full, clear, and exact description thereof, reference being had to the accompanying drawings, which form a part of this specification.

10 This invention relates to certain new and useful improvements in the construction and operation of devices for cutting gelatine capsules from the molds upon which capsules are formed.

15 The invention consists in the peculiar construction of the various parts and their combinations and operation, as more fully hereinafter described.

Figure 1 is a perspective view looking toward the front of the device. Fig. 2 is a like view taken from the reverse side. Fig. 3 is a cross-section through one of the series of cutters.

In the accompanying drawings, which form 25 a part of this specification, A represents the front, and B the rear, plate, through which are formed the coincident holes a b, and between these plates is a plate, C, of sheet rubber, with holes coincident with the holes a b, but of larger diameter. Ring cutters D, sharpened on their inner periphery or edge, are fitted into the holes in the rubber plate, and held in place by the front and rear plates, which are secured together by the rods 30 E and nuts e d. These rods also project from the reverse side of the device, and are provided with adjusting stop-nuts e. In order to allow these stop-nuts to be adjusted, the rods are suitably threaded; or any other form 35 of an adjustable stop may be employed without departing from the spirit of my invention.

In practice the stops are adjusted to the length the capsule is desired, such length being regulated by the distance between the 45 stop and the face of the plate B. The device then is grasped by the hand of the operator, and the projecting ends of the rods entered into coincident holes in a plate of molds, which I make the subject-matter of a distinct 50 application for a patent, and hence do not describe in this specification. The mold-pins of such mold-plate, being arranged in series coincident with the series of holes in this cut-

ting device, enter the ring cutters until the stops are brought into contact with the front 55 of such mold-plate. A rotary motion is then communicated to the plates carrying the ring cutters by the hand of the operator, which brings the cutting-faces into contact with the capsules on the mold-pins and cuts them off 60 in uniform lengths. The pressure necessary to perform this cutting is exerted through the rubber plate, the elasticity of which will allow of any slight variation of the mold-pins 65 without interfering with the perfect work of the cutters.

I am aware of the Patent No. 297,380, granted to James H. Glover, April 22, 1884, and make no claim to the construction shown therein as forming part of my invention.

I am aware that it is not new to employ in a capsule-cutting machine a cutter-plate constructed with an orifice surrounded by an annular beveled cutting edge projecting inwardly toward the center of the orifice.

I am also aware that it is not new to employ in a capsule-cutting-off device a ring cutter inserted in a rubber spring-plate and cutting upon its inner periphery.

What I claim as my invention is—

1. The combination, in a capsule-cutting machine, of an annular cutter sharpened on the inner edge and held in a suitable holder, a mold-pin attached to a suitable holder, and an adjustable guide attached to one of said 85 holders for regulating the position of the pin as to its length within said cutter, substantially as described.

2. In a capsule-cutter, a series of ring cutters set in a suitable holder, and a second 90 holder carrying a series of mold-pins, one of said holders being provided with a series of guide-rods and the other holder with a corresponding series of guide-holes in which said guide-pins work, substantially as described.

3. A capsule-cutting-off device consisting of the following elements: rigid front and rear plates, inclosing a spring-plate, through all of which are coincident holes, those in the spring-plate inclosing ring cutters, stops, and guide-rods, the parts being constructed, arranged, and operating substantially as and for the purposes set forth.

Witnesses: JOHN KREHBIEL.

H. S. SPRAGUE,
E. SCULLY.
